UNITED STATES PATENT OFFICE.

ALFRED E. HOLMES, OF CHICAGO, ILLINOIS, ASSIGNOR TO WILLIAM H. PLUNKETT, OF CHICAGO, ILLINOIS.

LIQUID DISPENSER.

Application filed September 3, 1921. Serial No. 498,197.

To all whom it may concern:

Be it known that I, ALFRED E. HOLMES, a citizen of the United States, residing at Chicago, in the county of Cook, and State of Illinois, have invented a certain new and useful Improvement in Liquid Dispensers, of which the following is a specification.

My invention relates to liquid dispensers and embodies improvements in the structure shown in my previous Patent No. 1,165,673 granted December 28, 1915. Experience with the previous form shows that leakage is difficult to prevent, owing partially to the fact that the inlet valve makes sliding contact with the inlet port, and when the devices are made in quantity, as good commercial practice demands, it is difficult to get all samples to fit close enough to prevent leakage. As a result of my present invention it is possible to employ a tapered or positively seating valve both for the inlet and outlet ports. This avoids the need of accurate fitting and produces at all times a tight closure. It also prolongs the life of the device, as abrasion does not cause the valves to leak.

In the accompanying drawings, which illustrate the invention, Figure 1 is a side elevation partly in section, of the complete device, showing the reservoir and its support as well as the valve mechanism.

Figure 2 is a vertical axial section of the valve mechanism showing the inlet valve in open position and the outlet valve in closed position. This is the normal position of the parts.

Figure 3 is similar to Figure 2 but shows the inlet valve closed and the outlet valve about to open.

Figure 4 is similar to Figure 3 but shows the outlet valve in open position.

Figure 5 is a plan section on the line 5—5 Figure 4.

Figure 6 is a plan section on the line 6—6, Figure 4, and

Figure 7 is a plan section on the line 7—7, Figure 2.

Like numerals denote like parts throughout the several views.

In the form illustrated, there is a container 1 supported upon a bracket 2 of any suitable design. The valve mechanism which embodies my invention is mounted at the bottom of the container and includes a valve casing or chamber 3 having an inlet port 4 at the top and an outlet port 6 at the bottom.

Said inlet port is here shown in the form of a ring screwing into the upper end of the chamber 3. Both the inlet and outlet ports have positive seats, for example, are tapered, so as to cooperate definitely and positively with the shoulders 8 and 10 of the inlet and outlet valves respectively. The inlet valve has an upstanding guide stem 12 which slides within the inlet port. The outlet valve has a depending guide stem 13 which slides within the outlet port and projects down far enough to form a handle by which it may be manipulated. Both the inlet and outlet valves are cut away at the side in the usual manner to permit the flow of liquid when the valves are in open position.

Within the chamber is a helical compression spring 16 which rests upon the outlet valve to yieldingly hold it closed. At the upper end this spring abuts the ring 4 of the inlet port. The chamber also contains an inner helical compression spring 18 which rests upon the outlet valve and at the upper end supports the inlet valve. For identification the inner spring 18 may be termed the "cushion spring" and its length is such that when the outlet valve is seated the inlet valve will be low enough to permit the flow of fluid through the inlet port and into the chamber 3. Said spring is long enough, however, to close the inlet valve before the outlet valve has risen sufficiently to permit the fluid to flow past the cut-away portion at the side of the stem.

In operation, under normal conditions the parts will occupy the positions shown in Figure 2, in which the outlet valve is seated and closed and the inlet valve is down in open position. This permits the chamber within the casing 3 to fill with the liquid soap or other fluid to be dispensed. If, now, the user wishes to obtain a charge of fluid, he pushes upward upon the valve stem 13. This compresses the spring 16, but as the inlet valve is free to rise, it does not, at first, compress the spring 18. It simply causes the inlet valve to rise until it seats and closes the inlet port, as shown in Figure 3. The parts are so constructed that this closing action will be completed before the cut-away portions of the stem of the outlet valve rise above the valve seat 6. The consequence is that at one point during the upward movement of the outlet valve the parts will occupy the position shown in Figure 3 in which the inlet

valve is closed and the outlet valve has risen from its seat but has not uncovered the outlet port. At such time both ports are closed, thus making it impossible to hold the valves 5 in such position that fluid can descend in a continuous flow from the container 1 out through the outlet port 6. The inlet valve closes by positively abutting its seat before the outlet valve opens. As the user continues 10 to elevate the outlet valve, the cut-away portion of the stem thereof rises above the valve seat 6 and uncovers the port, thus permitting the charge of fluid within the casing 3 to emerge.

15 A little reflection will show the superiority of my present construction over the one shown in my said prior patent. In my present device the inlet valve is positive acting in the sense that it definitely abuts its seat 20 instead of having a sliding movement of indefinite length, as in the prior construction. The new result is made possible by making the valves in two pieces instead of one and introducing a cushion spring for transmitting motion from the outlet to the inlet valve 25 and permitting the outlet valve to continue its upward movement after the inlet valve has been arrested by coming into contact with its seat. My present device retains all 30 the advantages of the old and possesses the added advantage of making a positive closure both at the outlet port and the inlet port. It also possesses longer life, for, in the case of a sliding cut-off, as with the inlet valve of the prior construction, constant 35 wear increases the size of the port and decreases the size of the stem of the valve. Consequently, even if the closure is tight when the device is new, continued wear tends 40 to produce leakage. With the present design where the engagement of the inlet valve with its valve seat is positive, abrasion does not tend to cause leakage. On the contrary, the action is similar to that of a self-grind-

ing valve and abrasion simply renders the fit 45 more perfect.

Having thus described my invention what I claim as new and desire to secure by Letters Patent is:

1. A liquid dispenser having a chambered 50 casing having shouldered valve seats at the inner and outer ends, inlet and outlet valves adapted to abut said seats, a stem on the outlet valve having a cut-away portion adapted to permit the exit of fluid from the 55 chamber, and a spring interposed between the two valves, said spring being short enough to permit the inlet valve to be away from its seat when the outlet valve is in contact with its seat and long enough to hold the inlet valve in engagement with its seat prior to the time when the cut-away portion 60 of the stem of the outlet valve reaches the outlet valve seat.

2. A liquid dispenser having a container 65 with a valve casing in the bottom, said casing being chambered and being provided with an inlet port and an outlet port, said ports both having positive seats facing inward toward the chamber, an inlet valve having a shoulder adapted to seat against the inlet valve seat and having a guide stem cut away at the side, an outlet valve having a shoulder adapted to seat 70 against the outlet valve seat and having a guide stem cut away at the side, the valve stem projecting through the outlet port to afford means for manipulating it, a spring for normally holding the outlet valve 75 seated, and a cushion spring actuated by the outlet valve and supporting the inlet valve and adapted to close the inlet valve before the cut away portion of the stem of the outlet valve uncovers the outlet port.

In witness whereof, I have hereunto subscribed my name.

ALFRED E. HOLMES.
